UNITED STATES PATENT OFFICE

HARRY L. LIBERTY, OF CHICAGO, ILLINOIS

UNIVERSAL CONNECTER AND SUPPORT

Application filed October 4, 1928. Serial No. 310,280.

This invention relates to a universal connector and support for supporting fixtures and the like on electric outlet boxes, and is useful for securing the outlet boxes to hanger strips when same are used.

Outlet boxes for electrical connections are at the present time secured to fastening strips or hangers applied to the framework of a building as the framework goes up and before the time that the fixtures are installed. The boxes are made with a plurality of apertures, closed by the metal of the box, which closures may be readily removed to make available any of such apertures for use in attaching fixtures or conduits and the like.

At the present time the outlet boxes are fastened to the strips or hangers by bolts or by slides on the strips to which the boxes may be subsequently fastened. Outlet boxes for wall brackets have to be deeper than the boxes for other outlets, and the slides have been found disadvantageous with respect to the use of the deep outlet boxes. Under some conditions, however, the boxes are put in place without hanger strips.

My invention is especially useful in connection with the application of deep outlet boxes for wall brackets or where brackets are to be built in such situations where it is difficult or almost impossible to apply fastening bolts through the strips. It also eliminates the necessity of the sliding box connector now in use. It is also useful without hanger strips for attaching fixtures and the like to the outlet boxes after same have been put in place, as it may be readily hooked through any of the openings in the box from the inside.

An object of my invention is to provide a connector for outlet boxes which may be readily applied anywhere along the supporting or fastening strips after the strips have been installed, and which is clamped in position on the strip with the box without the use of the usual bolts.

Another object of the invention is to provide a universal connector and support for outlet boxes which may be applied to a supporting strip anywhere along the same after installation of the strip, and which connector

is fastened in position by means readily accessible.

A further object is to provide a connector for outlet boxes which may be hooked over an attaching strip to receive an outlet box, and which is secured in position with the outlet box thereon by a single member.

Another object is to provide a universal member for attaching fixtures to outlet boxes without a hanger strip.

A further object is to provide a support for a fixture or conduit which may be readily and securely fastened in any of the several openings of the outlet box without the use of bolts, screws or the like.

A still further object of the invention is to provide a connector for outlet boxes which is economical to manufacture, strong and durable in use, quickly and readily applied and efficient for the purposes intended.

A yet further object of the invention is to provide a connector which may be hooked over a support for holding in place an outlet box, or which connector may be hooked into engagement with any of the holes in the box for securing fixtures or the connections to the box, and which connector is applied from the inside of the box, hooked and fastened in a selected position within the compass of the box and without requiring special fittings and the like.

The above and further objects of the invention will be apparent from the following description and drawings, and appended claims.

This invention (in a preferred form) is illustrated in the drawings and hereinafter more fully described.

According to the invention, the connector comprises a single member having a hollow cylindrical boss to receive the outlet box, and a hook having one open end to engage over the attaching strip with means for clamping the box and the member on the strip by the same nut or other clamp.

One form of the invention is shown in the accompanying drawings, and the views thereof are as follows:

On the drawings:

Figure 1 is a section through a ceiling with

a shallow outlet box secured in position by my connecter.

Figure 2 is a section through a wall showing a deep outlet box secured in position.

Figure 3 is an enlarged section through an outlet box and connecter secured to a supporting strip.

Figure 4 is an enlarged fragmentary plan view of an outlet box and an attaching strip, with a full elevation of the connecter.

Figure 5 is an elevational view of the other end of the connecter from that shown in Figure 4.

Figure 6 is a side elevation of the connecter with a nut on the threaded boss.

Figure 7 is a side view showing in full and dotted lines the manner of applying the connecter to an attaching strip or hanger.

Figure 8 is an enlarged fragmental section through an outlet box showing the connecter clamped in position to support a fixture or conduit.

As shown on the drawings:

Building frame members 1 and 2 have fastened thereto an attaching strip or hanger 3 of the usual kind. The strip is attached by nails 4 passing through one of the openings 5 in the strip 3 and into the frame members 1 and 2.

Figure 1 shows a shallow outlet box 6 fastened to the hanger or strip 3 by the connecter 7.

Figure 2 shows frame members 8 and 9, to which is attached by nails 10 a hanger or attaching strip 11. The attaching strip 11 has an offset portion 12 formed therein for the reception of the deeper outlet box 13 which is fastened by the connecter 7.

The connecter 7 comprises a cylindrical boss 14 which is hollow and which is threaded on the inside and the outside. A hook 15 is integral with the boss 14 and includes a flat surface 16 with shoulders 17 and 18 at the ends of the surface and arranged substantially perpendicular thereof for abutting the margins of the attaching strips to prevent lateral displacement or tipping of the box. The length of the hook and its end surfaces 19 and 21 is greater than the size of the aperture in the connection box thru which the hook is inserted from the inside of the box.

The connecter is made so that the hook has an open end 19 defining a recess between the surface 16 thereof and the surface defined by the outline 20. The outline 20 is curved and converges for at least a portion of its length towards the closed end of the hook 15 that is towards the shoulder 17. The ends of the hooks 19 and 21 are flat to rest against the back wall of the outlet box when the same is assembled on the strip by means of the connecter 7, and to rest against the rear of the walls of the box when inserted therein for supporting a fixture or the like.

Figure 3 shows a deep outlet box 13 at-

tached to the hanger or attaching strip 11 by the connecter 7. The connecter may be applied over the attaching strip or hanger anywhere along the length of the same by hooking the open end 19 thereof over the strip, as is shown in Figure 7. The connecter may be readily applied to the attaching strip as described.

The member 7 having the open hook and the flat faces 19 and 21 is inserted through any of the apertures 22 in the box, central or otherwise, from the inside of the box after same has been set and brought to a bearing with the flat faces 19 and 21 against the rear of the box and with the boss 14 projecting through the aperture for attachment thereto of a clamp and also a fixture or the like, whereby the fixture or the like may be readily supported without the use of the hanger strips.

The support 7 is hooked through an aperture in the box from the inside of the box as the open end of the hook and the depth of same readily allows the hook to pass over a portion of the box adjacent the aperture so as to enable the manipulation of the connecter for the purpose of fastening the hook and its end surfaces 12 and 21 to such aperture for engagement with the outer surface of the box adjacent the aperture.

As ordinarily used the outlet box, after the connecter has been hooked over the attaching strip, is placed over the boss 14 of the connecter so that the boss passes through a central or any of the usual circular holes 22 in the outlet box. A clamping member such as a nut 23 is then applied over the outer threaded surface of the boss 14 against the inner surface of the back wall of the outlet box and tightened. This brings the ends of the several parts into the position shown in Figure 3, and is tightened until the box is secured on the attaching strip.

The recess between the hook 15 and the boss shaped as it is permits ready application of the connecter to any attaching strip. The shoulders 17 and 18 prevent lateral displacement of the connecter when applied to the attaching strip.

Figure 8 shows the connecter applied to an outlet box by being clamped in one of the apertures 22 for supporting a fixture or conduit in position in the box, as sometimes it is necessary to so support a fixture or a conduit, by a holder or connecter. The connecter 7 in this figure is not hooked over a strip as the outlet box is supported by another similar connecter 7 or may be fixed in position by the plaster or other finishing material without a hanger strip.

It will be observed that installation of outlet boxes employing my connecter is simple. Attaching strips 3 or 11 (if used) or any other attaching strips may be secured on the framework of the building in the usual

manner. Whenever it is time for the application of the outlet boxes the boxes are connected by hooking one of the connectors over the attaching strip from the inside of the box and fastening the outlet box to the connector in the manner heretofore described.

The outlet boxes are of standard shape, size and arrangement, as are the attaching strips. My connector may be used with any standard boxes and strips.

While I have described more or less precisely the details of construction of my invention, yet I do not wish to be understood as limiting myself thereto, as I am aware that changes may be made in the arrangement and proportion of parts and that equivalents may be substituted, all without departing from the spirit and scope of my invention.

I claim as my invention:

1. A universal support for attaching fixtures and the like to outlet boxes comprising a member having an open ended hook for insertion through an aperture in the box from the inside of the box, said hook having end extensions providing faces for engaging the rear of box adjacent the apertures, said members also having a boss projecting through said aperture, and a clamp engaging the inside of said box and said boss for fastening said member in position to receive a fixture or the like.

2. A universal support for use with electric outlet boxes comprising a member having an open ended hook, a central boss and substantially flat faces adjacent the hook whereby said member may be hooked over a hanger strip for supporting a box thereon and also may be hooked through an aperture in said box for supporting a fixture on the box with the faces of said member engaging the outside of the box adjacent the aperture, and means engaging the inside of said box for clamping said member in position.

3. A universal connector for attaching outlet boxes to hanger strips, comprising a member having an open ended hook for engaging a strip and a portion of said box, a boss for receiving an outlet box, and a clamp on said boss for fastening said box and said member in position on the strip.

4. A universal connector for attaching outlet boxes to supporting strips, comprising a member having an open ended hook for engaging an attaching strip and a portion of said box, a threaded boss for receiving an outlet box, and a nut in threaded engagement with said boss for fastening said box and said member in position on a strip.

5. A universal connector for an outlet box comprising a single fitting having an open ended hook thereon arranged to hook over a supporting strip and to receive an outlet box thereon, said fitting being applicable from the inside of the box and means on said fitting acting against the inside of said box

for clamping said box and said member in any position along said strip.

6. In combination, a universal connector for an outlet box comprising a single member having a shouldered hook to engage about an attaching strip and the adjacent side of an outlet box, an outlet box on said connector, said member being applicable from the inside of the box through an aperture therein, and a clamp on said fitting acting against the inside of said box for fastening said box to said connector and said connector to said strip.

7. A universal connector for securing an outlet box to an attaching strip, comprising a single member having a hollow threaded boss, a shouldered hook integral with the boss having an open end for hooking over the strip from inside of the box, the end of the boss adjacent the hook being inclined to permit ready application of the connector to the strip, and a nut engaging said threaded boss for securing an outlet box thereon and fastening said member to said strip.

8. A universal connector for securing an outlet box to an attaching strip and applicable from inside of the box through an aperture therein, comprising a single member having a hollow threaded boss, a shouldered hook integral with the boss having an open end for hooking over the strip, said hook being longer than the size of the hole through which it is applied the end of the boss adjacent the hook being inclined to permit ready application of the connector to the strip, and a nut engaging said threaded boss inwardly of the box for securing an outlet box thereon and fastening said member to said strip, said inclined end of said boss converging from the open end of the hook towards the closed end of the same.

9. A universal connector and support for electric outlet boxes comprising a single member for receiving an outlet box and applicable from inside the box through an aperture therein, said member having an open ended hook for engagement over an attaching strip, and means cooperating with the boss for fastening the outlet box inwardly of the box and said member in position anywhere along said strip.

10. In combination an electric outlet box support including an attaching strip to be secured on the framework of a building, a box connector comprising a single fitting having an open ended hook at one end thereof to engage over the strip and a boss to receive an outlet box, an outlet box arranged over said boss, said connector being applicable from inside the box through an aperture therein for hooking engagement with a strip and means inwardly of said box for clamping said box on said connector, said means also clamping said connector to said strip.

11. A universal fixture support for an electric outlet box comprising a member hav-

- ing a hook for hooking through any of the several apertures in the box, a boss integral with the hook to project through the aperture, bearing surfaces integral with said hook for engaging the rear of the box adjacent the aperture, and means for securing said member in position to support a fixture.
12. A universal fixture support for outlet boxes comprising an outlet box, a member arranged to be hooked through an aperture in the box and have a bearing against the rear of the box adjacent the aperture, a boss integral therewith to project through the aperture and support a fixture thereon, and means engaging against the inside of said box for locking said member in said box.
13. A universal fixture support for outlet boxes, in combination with an outlet box, a member having a boss to project through any of the several apertures of said box, said member having an open ended hook at one end thereof which hook is applied in position by being passed through a selected aperture in said box from inside the box, said hook having an end thereof extended to bear against the outer surface of said box when secured in position, and means engaging said boss and said box inwardly of said box for securing said members to said box.
14. A universal fixture support including an outlet box having an aperture therein, an attaching connector having a hook end insertable through said aperture from the inside of the box for engaging a support, said hook having an extended portion for contacting with the outside surface of said box when in position, and a clamp engaging said member and bearing against the inside of the box for clamping said box and said member to a support, said member having means for co-operating with a fixture.
15. A universal fixture support including a stud having an open ended hook at one end; said stud being applicable to a support through an aperture in a connection box from inside of said box, said hook having faces for engaging the outer surface of the box adjacent said aperture, and a clamp engaging said stud inwardly of the box for securing all of said parts together in operative relation.
16. A universal fixture support for outlet boxes comprising a stud having a part thereof exteriorly and interiorly threaded, and having a hook extending from one end thereof, said hook having end bearing faces, said hook being insertable through an aperture in an outlet box from the inside of said box and so manipulated as to bring said bearing faces against the outside of the box adjacent the aperture, and a clamp on said stud acting against the interior of said box for fastening said parts together.
17. A universal fixture support for outlet boxes comprising a cylindrical member of uniform size from end to end, said member having a hook at one end which hook is of greater length than the transverse dimensions of said member, said member being applicable to a connection box by engaging said hook over the margin of an aperture in said box and moving the same laterally so that said hook passes through said aperture with the body of the member in said aperture, and with a part of the hook against a portion of the outer face of the box and a clamp engaging said member inwardly of the box for drawing said hook against the outside of the box adjacent the aperture.
- In testimony whereof I have hereunto subscribed my name.
- HARRY L. LIBERTY.
